UNITED STATES PATENT OFFICE.

WALTER B. STEPHENSON, OF MARION, INDIANA, ASSIGNOR TO DELTA ELECTRIC COMPANY, OF MARION, INDIANA, A CORPORATION OF INDIANA.

DESIGN FOR A FLASHLIGHT.

59,301.

Specification for Design.

Patented Oct. 4, 1921.

Application filed April 14, 1919. Serial No. 290,102. Term of patent 7 years.

To all whom it may concern:

Be it known that I, WALTER B. STEPHENSON, a citizen of the United States, residing at Marion, in the county of Grant and State of Indiana, have invented a new, original, and ornamental Design for Flashlights, of which the following is a specification, reference being had to the accompanying drawing, forming a part thereof.

In the drawing, the figure is a perspective of a flash light, showing my new design.

I claim:

The ornamental design for a flashlight as shown.

WALTER B. STEPHENSON.
